[57] **ABSTRACT**

Intermediate thrust elements are positioned between the cutters and the bearing pins of an earth boring bit. Each intermediate thrust element is located between a thrust surface on a bearing pin and a thrust surface on the associated cutter. The intermediate thrust elements aid stabilization of the rotating cutter, promote cutter rotation and extend the lifetime of the bit.

EARTH BORING BIT THRUST BEARING**BACKGROUND OF THE INVENTION**

The present invention relates to the art of earth boring and more particularly to a rolling cone rock bit. The present invention is especially adapted for use on that type of rock bit popularly known as a three-cone bit; however, its use is not restricted thereto and the present invention can be used in other types of rotary rock bits.

A three-cone rotary rock bit is adapted to be connected as a lower member of a rotary drill string. As the drill string is rotated, the bit disintegrates the formations to form an earth borehole. The three-cone rotary rock bit includes three individual arms that extend angularly downward from the main body of the bit. The lower end of each arm is shaped to form a spindle or bearing pin. A cone cutter is mounted upon each bearing pin and adapted to rotate thereon. Individual bearing systems promote rotation of the cone cutter. These bearing systems have traditionally been roller bearings, ball bearings, friction bearings or a combination of the aforementioned bearings. The cone cutters include cutting structure on their outer surfaces that serve to disintegrate the formation as the bit is rotated.

In addition to the rotational forces, the bit is subjected to a thrust load during operation. The weight of the drill string and the downward force applied by the rotary drill equipment apply a substantial thrust load upon the earth boring bit. In prior art earth boring bits, this thrust load was taken by a thrust button in the nose of the cone cutter which rotated against a hard faced surface on the inner end of the bearing pin and by the ball bearing system of the earth boring bit.

Prior art earth boring bits have experienced early failure because of their inability to support the extensive thrust loading. The thrust button and ball bearing systems have been unable to adequately support the thrust loads under certain drilling conditions and excessive wear of the elements subjected to the thrust forces has resulted in the cone cutters becoming disoriented with respect to the bearing pins with a consequent early failure of the bit. Certain earth boring bits used in the mining industry and popularly called blast or shothole bits have been constructed with an outer roller bearing system and an inner ball bearing system. The usual inner bearing system, generally a roller bearing or friction bearing, has been omitted. The space left by the omission of the inner bearing system has created a problem in that on occasion the cone cutter becomes disoriented with respect to the bearing pin resulting in early failure of the bit.

DESCRIPTION OF THE PRIOR ART

A general summary of typical bearing systems used in prior art rock bits is set forth in U. S. Pat No. 3,235,316 to J. R. Whanger patented Feb. 15, 1966. In FIG. 1 of this patent, a rock bit is shown having a roller-ball-friction bearing system. The innermost part of the bearing cavity formed in the cutter includes a thrust button which bears against the lowermost end of the bearing pin to absorb thrust forces. The ball bearing system of this bit also aids in absorbing the thrust forces. Another earth boring bit shown in this patent discloses an earth boring bit with a friction, ball-friction bearing system.

In U. S. Pat. No. 3,401,758 to M. L. Talbert patented Sept. 17, 1968, a jet type bit is shown that is employed in the drilling of blast or shotholes in mines. The bit shown in FIG. 2 of this patent includes an outer roller bearing system and an inner ball bearing system. It will be noted that a space exists between the reduced diameter lower end portion of the bearing pin and the associated inner surface of the cone cutter. This space has on occasion allowed the cone cutter to become disoriented on the bearing pin.

SUMMARY OF THE INVENTION

The present invention provides an improved bearing system for a rolling cone earth boring bit that will support thrust loads and prevent the cone cutters from becoming disoriented on the bearing pins. The present invention stabilizes the cone cutters, increases bearing life, reduces heat generation, provides an intermediate thrust element between the bearing pin and the interior of the cutter shell thereby providing a material that may be more compatible with the metals that are used for the bearing pin and the cutter shell and in general provides an improved earth boring bit. The intermediate thrust element is located between a thrust surface on the bearing pin and a thrust surface on the associated cone cutter. The intermediate thrust element is generally not affixed to the bearing pin or the cutter shell but is allowed to float freely between the bearing pin and the cutter shell.

It is therefore an object of the present invention to provide an improved rolling cone earth boring bit.

It is a further object of the present invention to provide a rolling cone earth boring bit that will support thrust loads better than bits of the prior art.

It is a still further object of the present invention to provide better stabilization of the cutters of an earth boring bit.

It is a still further object of the present invention to provide an intermediate element between the bearing pins and the cutters of an earth boring bit.

The above and other objects and advantages of the present invention will become apparent from a consideration of the following detailed description of the invention when taken in conjunction with the drawing.

BRIEF DESCRIPTION OF THE DRAWING

FIG. 1 illustrates an earth boring bit of the prior art.

FIG. 2 is a sectional view of one arm of an earth boring bit of the present invention.

FIG. 3 is an enlarged view of a portion of the bit shown in FIG. 2.

FIG. 4 illustrates one embodiment of intermediate thrust element of the present invention.

FIG. 5 illustrates diagrammatically some of the forces imposed upon the elements of an earth boring bit during drilling.

FIG. 6 illustrates another embodiment of an intermediate thrust element of the present invention.

DETAILED DESCRIPTION OF THE INVENTION

Referring now to FIG. 1 an earth boring bit of the prior art is shown and designated generally by the reference number 10. The bit 10 includes a body portion 12 having an upper portion 14 that is threaded to

allow bit 10 to be connected to a rotary drill string (not shown). A multiplicity of arms 16, 16', etc., extend from body portion 12. The lower portion of each arm 16, 16', etc., forms a bearing pin 18 that projects into a recess 20 formed in the associated rotary cutter 22. The cutter 22 is journaled on bearing pin 18 by roller bearings 24, ball bearings 26 and thrust button 28. A passage system 30 provides conduits to transport cooling fluid to the bearings.

The prior art earth boring bit 10 supports the entire thrust load with the ball bearings 26 and the thrust button 28. As the ball race 32 wears, the bit 10 tends to become unstable and an increased load is placed upon the roller bearings 26. The cone cutter 22 tends to become cocked with respect to the bearing pin 18 since cutter 22 wants to pivot about thrust button 28. The bit 10 consequently experiences early failure.

In addition, certain of the prior art bits are constructed without the usual inner bearing system. For example, the inner friction bearing system may be deleted in the roller-ball-friction type bits. The space left by the deletion of this bearing system aggravates the stabilization problem previously discussed. The space 34 in the prior art bit 10 is an example of this type of construction.

A single arm 36 of an earth boring bit constructed in accordance with the teachings of the present invention is shown in FIG. 2. The lower portion of arm 36 forms a bearing pin 38. The bearing pin 38 projects into a recess 40 formed in cutter 42. The cutter 42 is journaled on bearing pin 38 by roller bearing 44, ball bearings 46 and thrust button 48. A passage system 50 provides conduits to transport cooling fluid to the bearings. The cutter 42 includes a number of inserts 52 projecting from its outer surface that serve to disintegrate the formations during drilling. An intermediate element 54 is positioned in recess 50 between a thrust surface 56 on bearing pin 38 and a thrust surface 58 on cutter 42. The thrust element 54 is not affixed to the bearing pin 38 or the cutter 42 but is allowed to float freely around bearing pin 38.

Referring now to FIG. 3 an enlarged view of the intermediate element 54, bearing pin 38 and cutter 42 taken from area 3 of FIG. 2 is shown. The intermediate element 54 forms an annular ring that completely encircles the bearing pin 38. The central opening 60 of intermediate element 54 is of sufficient size that it does not restrict the cooling fluid emerging from passage system 50. A thrust surface 62 on intermediate element 54 bears against thrust surface 56 on bearing pin 38 and a thrust surface 64 bears against thrust surface 58 on cutter 42. The intermediate element 54 is free to rotate with cutter 42, remain relatively stationary with bearing pin 38 or rotate independently.

A top view of intermediate element 54 is shown in FIG. 4. The intermediate element 54 is constructed from a material that is compatible with the bearing pin material and the cutter material. In this embodiment, the intermediate element 54 is constructed of A.S.T.M.; B148, alloy 9C. The intermediate element 54 improves the performance of the bit and increases its lifetime. The intermediate element 54 helps support the thrust load, aids stabilizing of the bit, reduces heat generation thereby allowing the bearings to run cooler and provides a material that may be more compatible with the bearing pin and cutter materials.

In addition to the rotary forces applied to a bit during drilling, a substantial thrust load is imposed upon the bit. The bit must support both the weight of the drill string and the load applied to the drill string by the rotary equipment. The more important components of the thrust load and their effect on the bit are illustrated in FIG. 5. The thrust load consists of a horizontal component 66 and a vertical component 68. This load 66 and 68 must be transmitted from the cutter 72 to the bearing pin 74. Earth boring bits of the prior art would support the thrust load almost entirely by the thrust button 76 and the ball bearing system 78. Thus the components 66 and 68 would be transmitted to bit 70 as components 80, 82, 84 and 86. However, as the drilling operation proceeded, the bearing system 78 would tend to wear and enlarge ball race 88. As this happened, the cutter 72 would become disoriented on bearing pin 74 and an increasingly larger load component 90 placed upon the roller bearing system 92. The increased load 90 would produce an early failure of the roller bearing system 92 and a consequent early failure of the bit.

The provision of an intermediate element 94 between a thrust surface 96 on bearing pin 74 and a thrust surface 98 on cutter 72 helps support the thrust load, stabilizes cutter 72 and promotes rotation of cutter 72. Intermediate element 94 receives a portion of the thrust load as illustrated by components 100 and 102. This helps prevent cutter 72 from becoming disoriented upon bearing pin 74 thereby reducing the load component 90 acting against the roller bearing system 92. The intermediate element 94 may be left to float freely between cutter 72 and bearing pin 74 with the relative rotational speeds between intermediate element 94 and the surfaces 96 and 98 being less than if surfaces 96 and 98 were running directly against each other. In addition, intermediate element 94 may be constructed of a material that has greater friction bearing compatibility with the bearing pin material and the cutter material than they would have with each other.

In the embodiment of the invention shown in FIGS. 3, 4 and 5, the intermediate element 54 is constructed of materials that provide the surfaces 62 and 64 with anti-galling properties. The entire intermediate element may be constructed of the material having anti-galling properties or only the outer portion of the intermediate element may include the materials having these properties. The anti-galling materials may cover the entire surface or the anti-galling materials may be interspersed with other materials. In other embodiments of the invention, the intermediate element may be constructed of materials that provide its outer surfaces with hard wear resistant properties. For example, the intermediate element 94 shown in FIG. 5 may be constructed of A.I.S.I. 440C Stainless Steel. The hard wear resistant materials may cover the entire surface or the wear resistant materials may be interspersed with other materials. In the preferred embodiment of the invention the intermediate element has been shown as an annular ring; however, other shapes and forms of the intermediate element are contemplated. The intermediate element 104 shown in FIG. 5 consists of two semi-circular sections 106 and 108. The surfaces 110 and 112 of sections 106 and 108 must be compatible with the materials of the bearing pin and cutter that they run against. Sections 106 and 108 may be con-

structed of a hard wear resistant material selected from the group consisting of hardened steel, hardened aluminum bronze and tungsten carbide. Alternatively, sections 106 and 108 may be constructed of an anti-galling material selected from the group consisting of copper-based alloys, silver babbitt metal, aluminum and zinc. Instead of the entire intermediate element being constructed of one of the materials mentioned above, the intermediate element may be a mixture of the materials; a material may be plated on the outer surface of the intermediate element or the surface may be given the above-mentioned properties by other process. For example, the intermediate element may have surface grooves filled with an anti-galling material or the intermediate element may be a laminated 15 polytetrafluoroethylene fiber washer.

The embodiments of the invention in which an exclusive property or privilege is claimed are defined as follows:

1. An earth boring bit, comprising:
a bit body having an upper end connectable with a rotary drill string;
at least one bearing pin extending from said bit body, said bearing pin having a first portion with a first diameter, a second portion with a second diameter, said second diameter being smaller than said first diameter, and a bearing pin thrust surface between said first portion and said second portion; a cutter member rotatably positioned on said bearing pin, said cutter member having a first inner portion with a diameter larger than said bearing pin first diameter and a second inner portion with a diameter smaller than said bearing pin first diameter but larger than said bearing pin second diameter, with a cutter member thrust surface on the inner portion of said cutter member between said first inner portion and said second inner portion; bearing means between said bearing pin and said

cutter member for promoting rotation of said cutter member; and an intermediate element positioned between said bearing pin thrust surface and said cutter member thrust surface, said intermediate element having a first thrust surface opposite said bearing pin thrust surface and a second thrust surface opposite said cutter member thrust surface.

2. The earth boring bit of claim 1 wherein the first 10 and second thrust surfaces of said intermediate element have wear resistant characteristics.

3. The earth boring bit of claim 1 wherein the first and second thrust surfaces of said intermediate element have anti-galling characteristics.

4. The earth boring bit of claim 1 wherein the first and second thrust surfaces of said intermediate element have areas with wear resistant characteristics and areas with anti-galling characteristics.

5. The earth boring bit of claim 1 wherein said intermediate element is constructed from a material having anti-galling characteristics.

6. The earth boring bit of claim 1 wherein said intermediate element includes materials with wear resistant characteristics and materials with anti-galling characteristics.

7. The earth boring bit of claim 1 wherein the intermediate thrust element is constructed from a material selected from the group consisting of hardened steel, hardened aluminum bronze and tungsten carbide.

8. The earth boring bit of claim 1 wherein the intermediate thrust element is constructed from a material selected from the group consisting of carburized stainless steel, hardened alloy steel and hardened tool steel.

9. The earth boring bit of claim 1 wherein the intermediate thrust element is constructed from a material selected from the group consisting of copper-based alloys, silver, babbitt metal, aluminum and zinc.
